UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG-TYING TOOL.

Application filed September 24, 1919. Serial No. 325,972.

To all whom it may concern:

Be it known that I, ADELMER M. BATES, a citizen of the United States, residing at Chicago, in the county of Cook and State of Illinois, have invented a certain new and useful Improvement in Bag-Tying Tools, of which the following is a specification.

My invention relates to bag-tying tools and more particularly to a tool for twisting wire bag-ties, wherein the twisting operation is manually performed. The object of my invention is to provide a bag-tying tool which shall be short, light and compact and which after each operation shall automatically return to ready position. Other objects will appear from time to time in the course of the specification.

I illustrate my invention diagrammatically in the accompanying drawings as follows:

Figure 1 is an elevation of my tool engaging a bag-tie;

Figure 2 is an axial section of the tool;

Like parts are indicated by the same letters in all the figures.

A is a cylindrical handle exteriorly roughened as at B. It is screw threaded at C to receive the fixed plug D which has a spiral hole therethrough. E is a spiral rod within the handle adapted to pass through the spiral hole in the plug D. It is screw threaded at G whereby it is attached to the hook F. J is a plug having a piston end H which fits the interior of the cylindrical handle and is screw threaded whereby it received the screw threaded end I of the rod E. L is an eyelet in the end of the handle. K is a spiral spring about the rod and within the cylindrical handle. At one end it surrounds the plug J and bears against the head or piston H as shown. O is a wire tie about the end of the bag P.

Although I have illustrated an operative tool it will be understood that the shape, proportion and disposition of parts may be greatly varied without departing from the spirit of my invention. I have illustrated a hook adapted to engage a bag-tie with looped ends, but it will be obvious that a variety of hooks might have been used, adapted to engage any one of the many types of bag-ties now on the market.

The use and operation of my invention are as follows:

When the tool is in the position illustrated

in Figure 1, it is ready for use. The operator places the bag-tie about the mouth of the bag and engages it with the hook of the tube holding the bag top with one hand and the body of the tool with the other. He pulls them apart, drawing the tool toward himself. This, of course, causes the hook to rotate and tighten the tie because the spiral rod is forced to rotate on its passage through the spiral hole. This compresses the spiral spring. The roughened surface of the handle prevents it from rotating in the hand of the operator. When the hook is released or the pressure is withdrawn, the parts assume the position shown in Figure 1.

By placing the spindle rotating nut at the forward end of the tool body I greatly reduce the length. In the common bag-tying tools the nut is at the opposite end of the body, and the spindle length includes the waste portion which lies within the tool body, even at the extremity of the operating excursion.

In my form of tool the entire rod is withdrawn from the body save for that small portion which actually lies within the rod rotating nut. The piston or guide member centers the rod within the handle body.

I claim:

1. A wire twisting tool comprising a cylindrical handle, a fixed forward end with a spiral hole therein, a spiral rod within the handle, the rod carrying on its forward end a hook outside the handle and on its other end a piston like guide fitting in the cylindrical handle, a stub of smaller diameter than the handle projecting forward from said guide, and yielding means within the cylindrical handle for restoring the parts to normal position, comprising a spiral spring, one end engaging the forward end of the handle and the other engaging the guide.

2. A wire twisting tool comprising a cylindrical handle, a fixed forward end, a spiral rod within the handle, and means at the forward end adapted to rotate said spiral, the rod carrying on its forward end a hook outside the handle and on its other end a piston like guide fitting in the cylindrical handle, a stop projecting forwardly from said guide of lesser diameter than the interior of the handle but of greater diameter than the spiral rod, and a spiral spring, within the cylindrical handle for restoring the parts in normal position, said spiral spring being

adapted to be coiled about said stop when the end of the stop contacts the forward end of the handle.

3. A wire twisting tool comprising a cylindrical open ended tube, a screw threaded nut secured to one end thereof, a spiral rod slidably engaging said nut, a hook secured to the outer end of said rod, a piston-like guide secured to the inner end of said rod, and 10 adapted to close the remaining open end of the tube, and a spiral spring adapted to be compressed between the nut and the piston-like guide.
4. A wire twisting tool comprising an 15 open ended tubular handle and a spiral nut screw threaded into one end thereof, a spiral

rod adapted to pass therethrough, a hook in screw threaded engagement with the outer end of the spiral rod, and a piston-like guide in screw threaded engagement with the inner 20 end of said rod, a spiral spring adapted to be compressed between the nut and the guide, said guide adapted to close the end of the tubular handle when the spiral spring is in expanded condition. 25

In testimony whereof, I affix my signature in the presence of two witnesses this 17th day of September, 1919.

ADELMER M. BATES.
